UNITED STATES PATENT OFFICE.

WALTER KIESER, OF BERLIN, GERMANY, ASSIGNOR TO GENERAL ELECTRIC COMPANY, A CORPORATION OF NEW YORK.

ELASTIC-FLUID TURBINE.

No. 897,540.

Specification of Letters Patent. Patented Sept. 1, 1908.

Application filed January 31, 1907. Serial No. 355,005.

To all whom it may concern:

Be it known that I, WALTER KIESER, a citizen of Switzerland, residing at Berlin, Germany, have invented certain new and useful Improvements in Elastic-Fluid Turbines, of which the following is a specification.

The overload capacity of elastic-fluid turbines, particularly of large output, as heretofore constructed, is often limited by reason of the resultant high pressure in the early stages. For this reason it is necessary to permit the steam or other elastic fluid in the first stage to expand for normal load to the lowest possible pressure. In some cases the drop in pressure in the first stage is equal to about one half the initial pressure. Where the bucket wheel of the initial stage is fully supplied with fluid any increase in load is taken care of by increasing the pressure of the motive fluid, and in a partially supplied wheel by opening additional supply nozzles. In both cases an increase in pressure takes place within the turbine. In partially supplied turbines this increase in pressure can be avoided by opening additional nozzles to the second and succeeding stages, thereby permitting a greater amount of fluid to pass. A regulating mechanism of this character involves however for multi-stage turbines, great mechanical complications. In certain other cases the number of nozzles or other fluid-discharging devices in flow remain the same and the overload is handled by introducing high pressure motive fluid into one or more succeeding stages after the first, resulting in a pressure curve somewhat higher at an intermediate portion than the normal. In this instance, the fluid introduced to the intermediate stage or stages has to be throttled to reduce the pressure thereby losing a portion of the energy therein.

The present invention has for its objects to overcome the objectionable feature of the arrangements above noted and to improve the operation of elastic-fluid turbines by increasing their efficiency, while maintaining the pressure of the initial stage within certain predetermined limits and fully utilizing the available heat drop between the inlet and exhaust both for under and overloads, and this without changing the number or size of the nozzles in flow beyond the first stage or

unduly complicating the governing mechanism.

In the accompanying drawings, showing one of the embodiments of my invention, Figure 1 is a curve illustrating the pressure drop in the turbine; Fig. 2 is a longitudinal section of a multi-stage turbine arranged in accordance with my improvement; Fig. 3 is a partial plan view of the turbine; Fig. 4 is an end view of the same; and Figs. 5 and 6 are respectively a side elevation and plan of a slight modification.

In carrying out my invention the turbine is designed for the normal amount of steam, for example, corresponding to the pressure curve *a*, *b*, *c*, of Fig. 1. The wheel of the first stage is partially supplied, and a sufficient number of nozzles or other fluid-discharging devices are provided which can be put in service for increases in load. In order to avoid an undue increase in pressure in the first stage under conditions of overload, the motive fluid after it has given up a certain amount of its energy in performing useful work in the initial wheel is conducted or shunted wholly or partially around one, two, three or more stages depending upon the amount of the overload. The fluid thus shunted is conveyed by a conduit, as for example 20, (Fig. 3) containing a suitable controlling valve 21. Upon increasing the quantity of motive fluid entering the turbine under these conditions, the pressure in all of the stages after the first will rise. The quantity of fluid flowing through the turbine can be increased until the stage into which the additional fluid is directed has almost the same pressure as the first stage. If, for example, the additional fluid is directed from the first to the fifth stage, (Fig. 2), the pressure curve *a*, *b*, *d*, *e* is obtained in the case of maximum load. In this case the drop in pressure between *b* and *d* is sufficient only to take care of the losses due to friction, etc. The pressure in the fifth stage will be increased over that due to normal operation by an amount represented by *d*, *g*. Under this condition the second, third, fourth and fifth stages perform no work and serve only to transmit a portion of the working fluid from the first to the fifth stage. The apparatus may also be arranged for different degrees of overload and a plurality of nozzle groups supplied by

conduits 22, 23, are arranged in the first stage so as to utilize the entire pressure drop. In this case the motive fluid, depending upon the number of groups in flow, is directed from the first to the third stage by the conduit 24, from the first to the fourth by the conduit 25, and from the first to the fifth by the conduit 20. The pressure curves resulting from this are represented by *a*, *b*, *f*, *c*; *a*, *b*, *e*, *c*; and *a*, *b*, *d*, *c* (Fig. 1).

Each of the valves 21, 26 and 27 in the shunt conduits 20, 24 and 25 may with advantage be operatively connected with the corresponding valve admitting fluid to the first stage thereby eliminating danger of the operator increasing the inflow to the first stage without making suitable provision for its escape. The central group of nozzles 28 leading to the first stage are shown in section, Fig. 2, and a valve 29 is provided to control their action. The nozzles in the initial stage are arranged to convert a greater percentage of the pressure into velocity than are the subsequent stage nozzles 28^a. The cross-sectional area of the nozzles increases from the initial toward the exhaust to compensate for the increase volume of the motive fluid at the decreased pressure. The admission valves may be operated by hand or they may be operated by a suitable source of relay power under the action of a governor in a manner well understood. It may be assumed that the valve 23^a controls the motive fluid for the normal load and the valves 22^a and 29 that for the overloads, or that two of the valves control the normal load fluid and one the overload. For load conditions between the normal and degrees of overload represented by the full opening of the conduits 20, 24 or 25 throttling of the fluid is resorted to.

In Figs. 5 and 6 a throttling valve 30 is interposed in the common supply conduit leading to the normal-load valve 31 and to the overload valve 32 by means of which the amount of steam can be regulated within the limits between normal load and maximum load by throttling. In these figures only one shunt conduit 33 is provided between the first stage and one of the subsequent stages containing an automatic valve 34 which responds to pressure and opens upon a predetermined increase in pressure and closes when the pressure falls. In the present illustration an adjustable weight 35 is employed to obtain the proper opening and closing, but it may be replaced by a spring or other equivalent means, as is well understood.

The turbines shown are intended primarily for marine turbines although the invention is not necessarily limited thereto. The shaft 36 carrying the revolving element of the turbine is mounted in suitable alined bearings 37 and is provided with collars 38 to take the end thrust, the casing for the collar being omitted. In Fig. 2 the exhaust from the

turbine is discharged by an upwardly extending conduit 39, and in Figs. 5 and 6 by a downwardly extending conduit.

In the early stages the bucket wheels 40 are partially supplied with steam or other motive fluid, two rows of wheel buckets being shown in each stage with intermediate buckets 41 between extending the proper distance around the circumference for fractionally abstracting the energy. These stages are separated one from the other by walls, diaphragms or partitions 42. In the low-pressure end of the machine the wheel buckets are or may be mounted on a drum 43 with suitable stationary intermediate buckets between. In this part of the turbine the intermediates extend entirely around the circumference and all of the buckets are active. In other words, the early stages are partial flow while the later stages, as represented by the rows of wheel and intermediate buckets, are total flow. Since the wheels in the lower stages are fully supplied with fluid I omit the diaphragms and thus decrease the overall dimensions.

I have shown one conduit for conveying fluid from the high-pressure stage to a given stage of lower pressure, but it is to be understood that I may provide two or more conduits arranged in multiple. The conduits may be removable as shown, or they may be formed in the wheel casing at the time it is cast or subsequently.

From the description it will be apparent that when the machine is operating at a given load or at less than said load all of the stages will be in service, and that as the load is increased beyond the said given load the number of stages will be decreased until under conditions of maximum load the minimum number of stages will be in service. It will also be apparent that the path of the motive fluid flowing through the shunt conduit is in multiple with that flowing through the nozzles or other fluid discharging devices of the shunted stage or stages. In other words the motive fluid flows through the turbine in series for certain loads and in multiple through a part more or less great of the turbine and a passage or conduit for greater loads.

The revolving element of the turbine is shown mounted on the same shaft and having a single casing, but if desired the shaft and casing may be divided and arranged to drive the same or different loads.

The invention is shown in connection with a horizontal shaft machine, but it is also applicable to machines having upright shafts.

In accordance with the provisions of the patent statutes, I have described the principle of operation of my invention, together with the apparatus which I now consider to represent the best embodiment thereof; but I desire to have it understood that the appa-

ratus shown is only illustrative, and that the invention can be carried out by other means.

What I claim as new and desire to secure by Letters Patent of the United States, is,—

- 5 1. An elastic-fluid turbine comprising a plurality of stages and having an inlet and an exhaust in combination with a conduit for shunting one or more high pressure stages to prevent excessive pressure in a given stage or stages. 70
- 10 2. An elastic-fluid turbine comprising a plurality of stages and having an inlet and an exhaust, in combination with a conduit which receives motive fluid after it performs work in the initial stage and shunts it past one or more stages and discharges into a low pressure stage to prevent excessive pressure in the initial stage, and a means for governing the passage of fluid in the conduit. 75
- 15 3. An elastic-fluid turbine comprising a plurality of stages and having an inlet and an exhaust, in combination with a plurality of conduits for shunting one or more high-pressure stages. 80
- 20 4. An elastic-fluid turbine comprising a plurality of stages and having an inlet and an exhaust, in combination with a conduit for shunting one or more of the early stages to prevent excessive pressure, and a valve for controlling the passage of motive fluid through the conduit. 85
- 25 5. An elastic-fluid turbine comprising a plurality of stages and having an inlet and an exhaust, in combination with a conduit for shunting one or more of the early stages to prevent excessive pressure, and a valve responsive to pressure changes for controlling the passage of motive fluid through the conduit. 90
- 30 6. An elastic-fluid turbine comprising a plurality of stages and having an inlet and an exhaust, in combination with a conduit which receives the motive fluid after it has given up a certain amount of its energy to the rotating member and shunts it past one or more stages and discharges it into a succeeding stage. 95
- 35 7. An elastic-fluid turbine comprising a plurality of stages and having an inlet and an exhaust, in combination with a conduit which receives the motive fluid after it has given up a certain amount of its energy to the rotating member and shunts it past one or more stages and discharges it into a succeeding stage, and nozzles or other fluid-discharging devices which receive the motive fluid from the conduit before it performs further work and discharge it into a stage of lower pressure. 100
- 40 8. An elastic-fluid turbine comprising a plurality of stages and having an inlet and an outlet, in combination with devices discharging fluid against the buckets of the successive stages, the devices discharging fluid to the initial stage being arranged to cause a greater pressure drop than those in the subsequent stages, and a means shunting motive fluid past one or more stages under overload conditions. 105
- 45 9. An elastic-fluid turbine comprising a plurality of stages and having an inlet and an outlet, in combination with devices discharging fluid against the buckets of the successive stages, the devices discharging fluid to the initial stage being arranged to cause a greater pressure drop than those in the subsequent stages, one or more conduits for shunting motive fluid past one or more stages, and valve-controlled means for regulating the passage of fluid through the conduits. 110
- 50 10. An elastic-fluid turbine comprising a plurality of stages each having relatively rotating members, means for passing motive fluid through the stages in series for normal loads, and means for shunting one or more of the stages for greater load conditions. 115
- 55 11. An elastic-fluid turbine comprising a plurality of stages each having relatively rotating members, means for passing motive fluid through the stages in series for normal loads, and valve-controlled means taking motive fluid from one of the stages after it has performed useful work and shunting it past one or more stages under conditions of overload. 120
- 60 12. An elastic-fluid turbine comprising a plurality of stages each having relatively rotating members, means for passing motive fluid through the stages in series for normal loads, and means for decreasing the number of active stages when the load increases. 125
- 65 13. An elastic-fluid turbine comprising a plurality of partial flow stages, a plurality of total flow stages which are always in service, and means for decreasing the number of partial flow stages in service as the load increases. 130
- 70 14. An elastic-fluid turbine comprising a plurality of partial flow stages, a plurality of total flow stages all of which are normally in service, and a means receiving motive fluid after it has been through a partial flow stage and performed useful work and shunting it past one or more partial flow stages. 135
- 75 15. An elastic-fluid turbine comprising a plurality of partial flow stages separated from each other by walls, a plurality of annular or total flow stages wherein the rows of moving buckets are separated from each other by intermediate buckets only, fluid-discharging devices for the initial stage which convert a greater percentage of pressure into velocity than those of the subsequent stages, and means receiving motive fluid after it has performed work in the initial stage and shunting it past one or more of the subsequent stages for overload conditions. 140
- 80 16. An elastic-fluid turbine comprising a plurality of partial flow stages and a plurality of total flow stages and initial and stage fluid- 145

discharging devices, in combination with means for varying the number of discharging devices in service in the initial stage without changing those in service in the subsequent 5 stages, and valve-controlled means affording a shunt passage for the motive fluid around one or more of the stages and in multiple with the fluid-discharging devices of said stages.

10 17. A turbine comprising a plurality of stages, means for passing the motive fluid through the stages in series for certain load conditions, and means for passing the motive fluid in multiple through the stages and a 15 passage and at less than at initial pressure for greater load conditions.

18. In combination, a turbine which is divided into stages, each having movable buckets, a device located in one of the stages 20 which receives motive fluid, decreases its pressure and discharges the same against the buckets, and one or more conduits which receive the motive fluid subsequent to its passage through said device, and after shunting one or more stages discharge it into a stage 25 from which it passes into another stage to perform useful work, and an exhaust conduit.

19. In combination, a turbine which is di-

vided into stages, a means for causing a 30 greater drop in pressure of the motive fluid in the first than in any one of the subsequent stages, one or more controllable conduits which receive steam after it has passed through the said means and performed work 35 and after shunting past one or more stages deliver it to a stage from which it passes to perform work, and an exhaust conduit.

20. In combination, a turbine which is divided into stages, each containing movable 40 buckets, a device which produces a greater drop in fluid pressure than do the devices of the subsequent stages and also discharges fluid to the buckets, other fluid discharging devices for the remaining stages, a conduit 45 which receives fluid after its pressure has been decreased by the admission device and after shunting it past one or more stages discharges it back into the turbine, an automatically operating valve for controlling the 50 conduit, and an exhaust conveying means connected to the turbine.

In witness whereof, I have hereunto set my hand this 9th day of January, 1907.

WALTER KIESER.
